UNITED STATES PATENT OFFICE

HERMANN HILL, OF SYRACUSE, NEW YORK, ASSIGNOR TO SYRACUSE WASHING MACHINE CORPORATION, OF SYRACUSE, NEW YORK, A CORPORATION OF DELAWARE

IRONER

Application filed January 3, 1930. Serial No. 418,237.

This invention relates to a new and improved ironing machine.

My invention is particularly well adapted for use in homes and it is designed with the particular purpose of providing an ironing machine which will be easy to operate and which will be so constructed that the manipulation of the various parts thereof may be accomplished easily and quickly by the operator.

10 The main object of my invention is to provide an ironing machine which will embody all of the advantages of large and cumbersome machines but which, itself, is comparatively light and compact so that it may be transported from place to place with the minimum of effort.

Another object is to provide an ironing machine which is so constructed that the different types of ironing applicable for different types of material may be accomplished with the minimum amount of manipulation of the different controls of the machine.

Another object is to provide an ironing machine in which the rotation of the ironing roll will be automatically stopped when the ironing shoe is moved away from the roll.

Another object is to provide a means whereby the ironing shoe may be manually moved away from the ironing roll during the operation of the machine.

Another object is to provide a machine in which the operation of the ironing shoe will be automatically resumed after any manual movement of the shoe from the roll.

Another object is to provide a machine in which the rotation of the ironing roll may be manually stopped without interrupting the operation of the ironing shoe.

40 Another object is to provide a means whereby the operation of the ironing shoe may be electrically controlled.

Other objects and advantages relate to the size, shape and relation of parts, all as will more fully appear from the following description taken in connection with the accompanying drawings in which:

Figure 1 is a top plan view of my improved ironing machine.

Figure 2 is a section, partially in full, in the plane of the line 2—2 of Figure 8.

Figure 3 is a section on line 3—3 of Figure 6.

Figure 4 is an elevation, partially broken away, taken in the plane of the line 4—4 of Figure 7.

Figure 5 is a section on line 5—5 of Figure 3.

Figure 6 is a section, partially in full, on line 6—6 of Figure 1.

Figure 7 is a section on line 7—7 of Figure 6.

Figure 8 is a section on line 8—8 of Figure 6.

Figure 9 is a section on line 9—9 of Figure 11.

Figure 10 is a section on line 10—10 of Figure 6.

Figure 11 is a section on line 11—11 of Figure 6.

Figure 12 is a section on line 12—12 of Figure 1.

Figure 13 is a top plan view, partially broken away and partially in section, of the ironing roll, shoe, shoe support and drive shaft for the latter.

Figure 14 is a side elevation of the lever for the manual control of the ironing roll.

Figure 15 is a section on line 15—15 of Figure 14.

Figure 16 is a vertical section through one end of the ironing roll.

Referring to Figures 1 and 2, my ironing machine comprises a gear casing 1 having adjacent its upper end a laterally extending tubular boss 2 and having adjacent its lower end a second laterally extending tubular boss 3.

A supporting tube 4 has one end rigidly secured in boss 2 with its outer end extending laterally therefrom. A shaft 5 has its inner end journaled in a ball bearing 6 secured in the inner end of boss 2 and has its outer end journaled in a ball bearing 7 secured in the outer end of supporting tube 4.

Shaft 5 extends outwardly through and beyond the outer end of tube 4.

A tubular ironing roll 8 has secured in its inner end, as perhaps may best be seen from

Figure 6, an annular collar 9 braced in position by a circular plate 10. The collar 9 has on its inner face, a race 11 between which and the outer surface of boss 2 is interposed an annular roller bearing 12.

The outer end of roll 8 (Figure 2) has secured to the inner face thereof a circular plate 13. Plate 13 has secured to its inner face, as by bolts 14, a tubular member 15 through which shaft 5 extends to which shaft 5 is secured as by a key 16 for simultaneous rotary motion.

The outer end of shaft 5 extends through plate 13 and is threaded to coact with a nut 17 to secure roll 8 against axial displacement in relation to shaft 5.

Referring to Figures 2, 6 and 13, a tubular support 18 has one end rigidly secured in boss 3 and has its other end secured in a support or saddle 19, the lower end of saddle 19 being in the same plane as the bottom of casing 1.

Saddle 19 primarily functions as a bearing support for shaft 86 (hereinafter to be described) and, altho it is here shown as also functioning as a support for the ironer shoe 33 and its operating mechanism, such additional support for the shoe 33 is not necessary altho desirable.

30 A shaft 20 extends through tube 18 and has its inner end journaled in a ball bearing 21 secured in the inner end of boss 3.

The inner end of shaft 20 extends inwardly beyond the inner end of boss 3. The outer end of shaft 20 is journaled in a ball bearing 22 secured in the outer end of tube 18.

40 The outer end of shaft 20 extends outwardly beyond the outer end of tube 18 for connection with the ironer shoe support in a manner about to be described.

Although the ironer shoe may be supported in a variety of ways, I prefer to support the same in a new and improved way which way has been disclosed and claimed by me in a co-pending application for ironer shoe support filed by me October 18, 1929, Serial No. 400,709.

This manner of supporting the ironing shoe may best be seen Figure 12.

50 I secure to the outer end of shaft 20 as by a key 23 and a set screw 24 a yoke 25. Yoke 25 has at the rear thereof of a recess 26 having an internal shoulder 27.

55 On the upper end of yoke 25 and between the opposite sides thereof is pivotally mounted a rock arm 28 as by a pivot pin 29.

The lower end of rock arm 28 is curved outwardly and downwardly and carries a set screw 30 adapted to contact with the inner face of yoke 25. On the upper end of rock arm 28 is pivotally mounted an outwardly extending link 31 as by a pivot pin 32. On the outer end of link 31 is secured in any convenient way (a new and improved way is disclosed in my copending application filed

August 29, 1928, on shoe mounting for ironing machines, Serial No. 302,767) a shoe 33 provided with an internally located heating element 34.

The front face of shoe 33 is curved to conform to the curvature of the roll 8 with which it is adapted to contact.

Just beneath pivot pin 32 and in rock arm 28 I provide a set screw 35 adapted to contact with the rear face of shoe 33 to prevent the same from moving downwardly about the pivot 32 when the shoe 33 is out of contact with the roll 8.

A leaf spring 36 here shown as composed of four leaves of different lengths has its bottom end seated in the bottom of recess 26 and has its upper end in contact with the rear end of link 31.

In the bottom of yoke 28 is positioned a set screw 37 which is adapted to be screwed inwardly against the lower end of spring 36 to cause the same to be forced against the shoulder 27.

The shoulder 27 functions as a fulcrum for the spring 36 so that the pressure of the upper end of spring 36 against the rear end of link 31 may be increased by screwing inwardly the set screw 37 against the lower end of spring 36.

In order to vary the angular relation of rock arm 28 to yoke 25 which in turn will vary the position of shoe 33 in relation to roll 8, the actuating parts being at rest, set screw 30 is provided.

Rock arm 28 being pivotally mounted on the upper end of yoke 25, it will be obvious that if set screw 30 is screwed inwardly through the lower end of rock arm 28 with its forward end abutting against the face of yoke 25, such lower end of rock arm 28 will be moved outwardly from yoke 25 which will cause the upper end of rock arm 28 to be moved in the opposite direction.

This outward movement of the upper end of rock arm 28 carrying link 31 will cause shoe 33 to be moved outwardly and away from roll 8. Conversely, if set screw 30 is screwed outwardly in the lower end of rock arm 28, such lower end will be permitted to move towards yoke 25 carrying the upper end of rock arm 28 inwardly to move shoe 33 towards roll 8.

When shoe 33 is out of contact with roll 8, the lower end of rock arm 28 carrying set screw 30 will be moved towards and held firmly in contact with yoke 28 due to the fact that spring 36 will tend to move the upper end of rock arm 28 inwardly about the pivot 29 and this movement will cause the lower end of rock arm 28 to be moved outwardly into contact with yoke 25.

The amount of pressure exerted by shoe 33 against roll 8 is determined by the tension of spring 36 because of the fact that after shaft 20 is rotated in a manner hereafter to be de-

scribed to carry the shoe 33 into contact with the roll 8, a slight additional movement of rotation of shaft 20, shoe 33 being in contact with roll 8, will cause rock arm 28 to be moved about its pivot 29 and this will cause set screw 20 to move out of contact with yoke 28 so that the shoe 33 will be held under pressure contact with the roll 8 solely by the spring 36.

This position of parts is shown in Figure 12.

On lower rear face of casing 1 is provided a motor housing 38 in which is positioned an electric motor 39 indicated in broken lines on Figure 8.

The armature shaft 40 of the motor 39 is secured as by a coupling 41 to the end of the shaft 42. Shaft 42 has one end journaled in a ball bearing 43 secured in casing 1 and has its opposite end journaled in a ball bearing 44 also secured in casing 1.

Shaft 42 is provided with a worm 45.

Referring to Figure 6, a shaft 46 is positioned in housing 1 in parallel relation to shafts 5 and 20 and has its outer end journaled in a ball bearing 47 secured in the outer end of casing 1 and has its inner end journaled in ball bearing 48 secured in the inner side of casing 1.

A spur gear 49 is rotatably mounted on shaft 46 and is provided with oppositely extending hubs, one of said hubs being journaled in a ball bearing 55. On the outer end of spur gear 49 is mounted a worm gear 50 secured to spur gear 49 as by a key 51. Worm gear 50 has an outwardly extending hub 52 between which and shaft 46 is interposed a ball bearing 53.

On the inner hub of spur gear 49 is secured as by a key 53' a clutch member 54 (see Figures 3, 6 and 11).

On the outer end of the inner hub of spur gear 49 is positioned a ball bearing 55.

A clutch and cam member 56 is rigidly fixed by press fit upon shaft 46 and this shaft in turn has its inner end located in a ball bearing 48 and its outer end in ball bearing 47 so that the clutch and cam member 56 rotates on ball bearings 48 and 47 through the shaft 46 as a medium. The spur gear 49 rotates in ball bearing 55, which is housed in the clutch member 56, and in ball bearing 53 through the medium of the hub of the worm gear 50, the worm gear 50 being rigidly secured by key 51 upon outer hub of spur gear 49.

The outer end of member 56 has pivotally mounted thereon as by a pivot pin 57 (Figure 3) a dog 58 adapted to engage slots 59 in clutch member 54.

Dog 58 carries an inwardly extending pin 60 in engagement with a coil spring 61 (Figure 7) adapted to move dog 58 about its pivot 57 to bring it into engagement with a slot 59 in clutch member 54.

Adjacent the inner face of dog 58 and piv-

otally mounted on pivot pin 57 is a plate 61' having an outwardly extending portion 62 in spaced relation to the end of dog 58. Such end of dog 58 is provided with an aperture 63 (Figure 5) in which is positioned coil spring 64.

A ball 65 is interposed between the end of spring 64 and end 62 of plate 61. A saddle shaped member 66 (Figure 11) has its lower end pivotally mounted in casing 1 on pivot pins 67 and 68.

Member 66 is adapted to be moved about its pivots towards and from dog 58 to bring one of its upwardly extending and opposed ends 69 or 70 into registration with the end 62 of plate 61.

When one of the ends 69 or 70 is in the path of movement of dog 58 the dog 58 will be held upwardly out of contact with the clutch member 54.

Conversely when the member 66 is moved about its pivot to carry the ends 69 and 70 out of the path of movement of dog 58 such dog 58 will through spring 61 be moved about its pivot 57 to bring it into engagement with the clutch member 54.

The member 56 has on its inner end a circular portion 71 eccentrically mounted in relation to the axis of shaft 46.

A ring 72 (Figure 7) encircles member 71 and is provided with a downwardly extending split yoke 73 through which extends a pivot pin 74.

A ball bearing 75 has its inner race mounted on pin 74 and has its outer race extending through a slot in ring 72 into contact with the periphery of member 71. Member 71 has a flattened portion shown at —a— on Figures 7 and 10 for a purpose hereafter to be described.

A yoke 76 has one end pivotally mounted on the outer ends of pin 74 and has its other end pivotally mounted on a rock arm 77 (Figures 7 and 10) which is secured as by a key 78 and set screw 79 to shaft 20.

A latch 80 has its lower end pivotally mounted in yoke 76 as by a pin 81 and has its upper end adapted to engage a shoulder 82 on arm 77.

To arm 77 is secured an upwardly extending link 83 to the upper end of which is secured a coil spring 84. Coil spring 84 has its upper end secured as by a pin 85 to casing 1 and is adapted to urge upwardly arm 77.

A shaft 86 (Figures 1 and 7) has one end journaled in the saddle 19 and has its other end journaled in casing 1.

Shaft 86 extends inwardly into casing 1 and has secured on the end thereof a crank arm 87.

A link 88 connects the lower end of crank arm 87 and the upper end of latch 80 so that the rotary movement of shaft 86 will cause the lower end of crank arm 87 to be moved in-

75

80

85

95

100

105

110

115

120

125

130

wardly and this in turn through link 88 will cause latch 80 to be moved inwardly out of registration with shoulder 82 on crank arm 77.

5 A spring 89 encircles shaft 86 and normally holds shaft 86 in a position to hold the lower end of crank arm 87 outwardly and the latch 80 in registration with the shoulder 82 on crank arm 77.

10 For the purpose of providing a convenient means for rotating the shaft 86, I provide an upwardly extending shaft 90 secured to shaft 86 and carrying on its upper end a knob 91.

15 For the purpose of limiting the upward movement of crank arm 77 I provide in casing 1 a stop 92 positioned in the path of movement of the crank arm 77.

The movement of the roll 8 is controlled by 20 means of the following mechanism. (Figures 4, 6, 7 and 11).

The inner end 93 of shaft 5 is reduced in size to form a shoulder 94. A spur gear 95 is rotatably mounted on the reduced end 93 25 of shaft 5 with one face abutting against the shoulder 94 and is secured in position on shaft 5 by means of a nut 96 which is in threaded engagement with the end of shaft 5.

The inner face of gear 95 carries a circular 30 clutch member 97 having circumferentially spaced jaws preferably tapered. A second clutch member 98 provided with jaws preferably tapered adapted to engage clutch member 97 is slidably mounted on shaft 5 35 and is keyed thereto as by a key 99.

For the purpose of moving clutch member 40 98 into and out of contact with clutch member 97, I provided a U-shaped shifting member 100 having one of its lower ends pivotally mounted in casing 1 as by a pivot pin 101 and having its other end pivotally mounted in casing 1 as by a pivot pin 102.

One end of member 100 extends downwardly below the pivot 102 and is provided 45 on its inner face with a rotatably mounted roller 103 for a purpose hereinafter to be described.

On the upper end of member 100 are provided opposed inwardly extending rollers 50 104 and 105 which rollers are positioned between the rear face of the jawed end 106 of clutch member 98 and an annular rim 107 formed on the rear end of clutch member 98.

The movement of member 100 about its 55 pivots 101 and 102 will cause the rollers 104 and 105 to contact either with the rim 107 to move the clutch member 98 out of registration with the clutch member 97 or with the rear face of the jawed end 106 to move clutch member 98 into registration with clutch member 97.

A spiral spring 108 has one end encircling 60 a post 109 secured in casing 1 and has the other end encircling a post 110 secured on clutch member 98 to normally urge such

clutch member 98 towards and into registration with clutch member 97.

For the purpose of moving member 100 about its pivot to disengage clutch member 98 from clutch member 97, I provide in housing 1 a rotatably mounted shaft 111 carrying on its inner end a cam member 112 adapted to contact with member 100 above the pivot 101 to move such member 100 about its pivot and into contact with rim 107 on clutch member 98. 70

On the other end of shaft 111 is provided a lever 113 to provide a convenient means for manually rotating shaft 111. 75

Lever 113 (Figures 14 and 15) carries a 80 slidably mounted pin 114 normally spring pressed outwardly by a coil spring 115, the outward movement of pin 114 being limited by a transverse pin 116 carried adjacent the inner end of pin 114 and adapted to contact 85 with lever 113.

In casing 1 is provided an aperture 117 adapted to receive the inner end of pin 114 when the same is in registration therewith and such pin 114 is pressed inwardly against 90 the action of spring 115.

The relation of parts is such that when pin 114 is in registration with aperture 117 cam member 112 will have moved member 100 about its pivot to carry clutch member 98 95 out of registration with clutch member 97.

Spring 108 will continue to exert pressure against member 100 and therefore against cam 112 and will therefore cause shaft 111 to be rotated to carry lever 113 to its normal 100 position whenever the pin 114 is moved outwardly from aperture 117.

The pressure exerted by spring 108 on the parts just described will cause pin 114 to be held in aperture 117 by friction against the 105 pressure of spring 115 which is a comparatively light spring as compared to spring 108.

When pin 114 is in aperture 117 and it is desired to return the parts to the normal position, it is only necessary to touch the end of lever 113 with sufficient force to relieve pin 114 from any tension from spring 108 for when this is done the pin 114 will be moved outwardly from aperture 117 by means of spring 115 and when lever 113 is thus released it will be returned to its normal position through the action of spring 108. 110

In Figure 15 I have shown in heavy lines the relation of parts when pin 114 is positioned in aperture 117 and I have indicated 115 in dotted lines the position of pin 114 when the same has been allowed to move outwardly out of registration with aperture 117.

For the purpose of providing an automatic means whereby member 100 may be moved about its pivot to move clutch member 98 out of registration with clutch member 97, I provide on member 56 an outwardly extending lug 118 having a cam surface 119 adapted, when member 56 is rotated, to contact with 120 125

130

5 roller 103 carried on member 100 to force the lower end of member 100 forwardly to move such member 100 about its pivot, which movement will cause clutch member 98 to be carried out of engagement with clutch member 97.

10 For the purpose of controlling the movement of the member 66 which itself controls the operation of the clutch composed of members 54 and 58, I provide a dual means, one manually controlled and the other electrically controlled.

15 The manual control comprises a shaft 120 rotatably mounted in casing 1 on the outside end of which I provide a lever 121 to permit easy manual manipulation thereof.

20 On the inner end of shaft 120 and secured thereto as by a pin 122, I provide a member 123 having a downwardly extending arm 124 adapted to contact with member 66 above its pivot 68. The bottom end of arm 124 is bent outwardly and forwardly and is adapted to contact with a set screw 124' carried on the side of a boss 68' on casing 1 to limit the 25 movement of member 123 about its pivot in one direction.

30 On the other end of member 123, I provide an upwardly extending member 125 having an offset arm adapted to contact with a set screw 125' carried on the side of a boss 101' on casing 1 to limit the movement of member 123 about its pivot in the other direction.

35 A spring 126 encircles shaft 120 having its upper end abutting against the offset end of arm 125 and having its lower end engaged with a hook-like member 127 which extends laterally from a depending leg 128 on member 66.

40 The disposition of spring 126 is such that it tends to hold the bottom end of member 66 outwardly and the upper portions thereof 45 69 and 70 in the path of movement of the dog 58. This movement of member 66 is limited due to the fact that member 66 will contact with arm 124 which is held against movement by set screw 124'.

45 When the lever 121 is moved downwardly to rotate shaft 120 the lower end of the arm 124 on member 23 will bear against member 66 to carry the upper portion thereof outwardly and to move the parts 69 and 70 of said member 66 away from the path of movement of dog 58. This movement of parts is limited because of the fact that member 125 will contact with set-screw 125'.

50 The construction just described can best be seen from Figures 9 and 11 as can the construction of the electrical control about to be described.

55 60 The electrical control for the parts just described comprises an electro-magnet 129 having an armature 130 pivotally mounted on the frame thereof. On the lower end of armature 130 is provided a clip 131 adapted to engage the lower portion 128 of member 66.

It will be obvious that when the magnet 129 is magnetized the armature 130 will be moved towards the magnet 129 carrying with it lower end 128 of member 66 which will cause member 66 to be moved about its 70 pivots 67 and 68 to cause the portions 69 and 70 of member 68 to be moved out from the path of movement of the dog 58.

When the magnet 129 is demagnetized, the spring 126 will cause the member 66 to 75 return to the normal position.

I have not here shown a switch for controlling the magnet 129 but I prefer to use a foot operated switch connected to a lead so that the operator may actuate this part 80 of the mechanism and still have both hands free.

The relation of parts is such that when the yoke 76 is in the lowered position the arm 77 will also be in the lowered position 85 and the shoe 33 will be in pressure contact with the roll 8.

With the parts in this position, the flat portion —a— of the cam member 71 will be in the bottom position and will be in opposed relation to the ball bearing 75 so that the thrust from the shoe 33 through the various parts which connect it to the ring 72 will be carried solely by such ring and not to any degree by the ball bearing 75. 90

95 Assuming that the parts just described are in the position shown in heavy lines on Figure 10 and the shaft 90 is manipulated to release the latch 80 from the shoulder 82 on arm 77, the spring 84 through the link 83 will carry the arm 77 upwardly to the position shown in dotted lines on Figure 10 and this in turn will carry the shoe 33 outwardly from the roll 8 to the position also indicated in dotted lines on Figure 10. 105

110 If the clutch members 54 and 58 are then permitted to come into engagement to cause the rotation of member 56, the inner end of yoke 76 will be carried upwardly by the movement of the cam 70 until the latch 80 is raised to the shoulder 82 on member 77 and into the position shown in dotted lines on Figure 10. When latch 80 reaches this latter position it will be pulled outwardly by the action of spring 89 into engagement with the shoulder 82 so that the actuating parts for the shoe 33 will be again locked together in the normal operating position. 115

120 When the ring 72 is in the lowermost position and the shoe 33 is in pressure contact with the roll 33, the clutch members 106 and 97 will be held in engagement by the spring 108 acting on the shifting member 100.

125 With the parts in this relation the roll 8 will continue to revolve so that materials to be ironed will be carried downwardly on roll 8 and between it and shoe 33.

130 With the parts in this position the cam surface 119 on the lug 118 carried on mem-

ber 56 will be out of engagement with the roller 103 carried on member 100.

When, however, cam 72 is further rotated to raise the yoke 76 to the highermost position, which movement will cause the shoe 33 to be moved away from the roll 8, the cam surface 119 will contact with the roll 103 to cause the member 100 to be moved about its pivots against the action of spring 108 to move out of engagement the clutch members 106 and 97 and therefore permit the roll 8 to come to rest.

If, for example, it is desired to iron or press material such as, for example, a pair of trousers, it is preferable to move the shoe 33 into and out of contact with the roll 8 while the latter is at rest.

When it is desired to operate the ironer under these conditions, the operator moves the lever 113 downwardly and pushes the pin 114 into engagement with the aperture 117. This movement of lever 113 will cause the cam 112 on the shaft 111 to bear against the member 100.

This will cause the member 100 to be moved about its pivots to cause clutch member 106 to move out of engagement with the clutch member 97 to permit the roll 8 to come to rest and the parts will remain in this position until the operator releases lever 113 and permits it to be returned to the normal position through the action of spring 108.

For the purpose of insuring a complete disengagement of clutch member 58 from clutch member 54 so that there may be no possibility of the two touching when in the disengaged position with resulting noise and vibration, I have provided the plate 61 shown on Figure 5.

When the member 66 is out of the path of movement of the clutch member 58 and such clutch member 58 is in engagement with clutch member 54 and it is then desired to separate clutch members 58 and 54, the member 66 in the manner heretofore described is moved about its pivots so that either the portion 69 or the portion 70 of member 66 will be moved into the path of movement of clutch member 58.

The portion 62 on plate 61 will then be brought into contact with, for example, the portion 69 on member 66. The dog 58 will continue its movement against the action of spring 64 until the dog 58 contacts with the portion 62.

The portion 62 being held against movement by the portion 69, the further movement of dog 58 will be interrupted so that the continued rotation of clutch member 54 will cause dog 58 to be moved about its pivot 57 and out of engagement with the slot 59 in which it was positioned. When dog 58 is freed from clutch member 54 the spring 64 will cause dog 58 to be moved upwardly a

further distance so that it will be in spaced relation with member 54.

For the purpose of limiting the movement of plate 61 about its pivot 57, I provide on the end of plate 61, an offset arm 62' adapted to contact with a shoulder 63' on member 56.

Roll 8 is usually provided with a cushioning covering of textile material indicated at 132.

Although none is here shown, it will be understood that I provide a switch for starting and stopping the motor 39 and I also provide a lead from such motor 39 so that it may be connected to any convenient source of potential.

It will also be understood that a switch is provided for connecting the heating element 34 to the circuit which is connected to the source of potential.

The ironing machine here disclosed is particularly well adapted to be used in ironing or pressing different types of materials because of the fact that it may be operated in a number of different ways depending upon the material which it is desired to subject to the operation of the machine.

For example, the roll 8 may be permitted to rotate continuously while shoe 33 is in pressure contact therewith or the roll 8 may be left at rest while the shoe 33 is moved into and out of pressure contact with such roll. Or, if desired, during the ironing operation the shoe 33 may be caused to be moved out of pressure contact with the roll 8 and the roll 8 allowed to come to rest to permit the arrangement of clothes on the roll.

Furthermore, I provide a manual means for moving the shoe 33 out of contact with the roll 8 irrespective of the other mechanism of the machine.

This latter means is provided so that clothes positioned between the shoe 33 and the roll 8 may be removed therefrom even if the machine should be stopped, through the blowing of a fuse or from some other cause, while the heated shoe 33 was in pressure contact with the roll 8.

If the shoe 33 has been manually moved away from the roll 8 and the machine then resumes its operation the shoe 33 will, as above described, be automatically reconnected to the operating mechanism without any action on the part of the operator.

Referring to Figures 1 and 16, the outer end of shoe 33 has the rear side curved inwardly and outwardly as shown at 33'. This construction is a decided improvement over any ironing shoes known to the art in that it permits the operator to retain hold of the article to be ironed up to the point where it passes underneath the shoe without any liability of the hand of the operator coming into contact with the heated shoe. Such action on the part of the operator is essential

when certain articles such as ruffles or collars are to be ironed.

I have here shown a specific structure and form and relation of parts, but it will be understood that various changes may be made in the size, shape and relation of parts without departing from the spirit of my invention, for although I have shown and disclosed a specific structure and form of part 10 as an exemplification of an embodiment of my invention I do not desire to restrict myself to the exact size, shape or relation of parts as various changes may be made within the scope of the appended claims.

15 I claim:

1. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, a ring secured to the link, a cam member positioned in the ring, a source of power, a normally inoperative clutch between the cam member and the source of power, means for making the clutch operative, and automatic means for making the clutch inoperative when the cam member is in a selected one of a plurality of positions in relation to the ring.

2. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, means for manually unlatching the latch, a ring secured to the link, a cam member positioned in the ring, a source of power, a normally inoperative clutch between the cam member and the source of power, means for making the clutch operative, and automatic means for making the clutch inoperative when the cam is in a selected one of a plurality of positions in relation to the ring.

3. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, means for manually unlatching the latch, a spring for returning the latch to the latching position when the latch is in a given position with relation to the arm, a ring secured to the link, a cam member positioned in the ring, a source of power, a normally inoperative clutch between the cam member and the source of power, means for making the clutch operative, and automatic means for making the clutch inoperative,

tive when the cam is in a selected one of a plurality of positions in relation to the ring.

4. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, a ring having a slot secured to the link, a cam member positioned in the ring, a ball bearing mounted on the ring and extending through the slot in the ring in contact with the periphery of the cam member, a source of power, a normally inoperative clutch between the cam member and the source of power, means for making the clutch operative, automatic means for making the clutch inoperative when the cam member is in a selected one of a plurality of positions in relation to the ring, and means for stopping the rotation of the roll when the cam member is in a given position in relation to the ring.

5. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, a ring having a slot secured to the link, a cam member having a flat portion on its periphery positioned in the ring, a ball bearing mounted on the ring and extending through the slot in the ring in contact with the periphery of the cam member at all times except when it is in opposed relation to the flat portion on the cam member, a source of power, a normally inoperative clutch between the cam member and the source of power, means for making the clutch operative, automatic means for making the clutch inoperative when the cam member is in a selected one of a plurality of positions in relation to the ring, and means for stopping the rotation of the roll when the cam member is in a given position in relation to the ring.

6. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, a ring having a slot secured to the link, a cam member having a flat portion on its periphery positioned in the ring, a ball bearing mounted on the ring and extending through the slot in the ring in contact with the periphery of the cam member at all times except when it is in opposed relation to the flat portion on the cam member, a source of power, a normally inoperative clutch between the cam member and the source of power, means

for making the clutch operative, and means for stopping the rotation of the roll when the flat portion on the cam member is in opposed relation to the ball bearing.

5 7. In an ironing machine, provided with a roll, a shoe cooperating therewith, said shoe having a portion of one end less in thickness from the face to back than the thickness of the body of the shoe.

10 8. In an ironing machine, having a roll, and a shoe cooperative therewith, said shoe having inner and outer walls and having a relatively small portion of one end reduced to a thickness approximately equal to the thickness of the inner wall.

15 9. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, a cam member cooperating with the link, a source of power, a normally inoperative clutch between the cam member and the 20 source of power, means for making the clutch operative, and automatic means for making the clutch inoperative when the cam member is in a selected one of a plurality of positions in relation to the ring.

30 10. In a device of the class described, a roll, means for rotating the roll, a shoe, means for moving the shoe into and out of contact with the roll including a shaft, an arm secured to the shaft, a link having one end pivotally mounted on the arm, a latch for holding the link and the arm against relative movement, means for manually unlatching the latch, a spring for returning the latch to the latching position when the latch is in a given position with relation to the arm, a cam member cooperating with the link, a source of power, a normally inoperative clutch between the cam member and the 35 source of power, means for making the clutch operative, and automatic means for making the clutch inoperative when the cam member is in a selected one of a plurality of positions in relation to the ring.

40 45 50 In witness whereof I have hereunto set my hand this 30 day of October, 1929.

HERMANN HILL.
